UNITED STATES PATENT OFFICE.

GEORGE STRAW, OF CONSTANTINE, MICHIGAN, ASSIGNOR OF TWO-THIRDS
TO SAMUEL W. HARVEY AND JOHN GREGG, OF SAME PLACE.

SHIFTING-RAIL FOR VEHICLES.

SPECIFICATION forming part of Letters Patent No. 310,474, dated January 6, 1885.

Application filed October 20, 1884. (No model.)

To all whom it may concern:

Be it known that I, GEORGE STRAW, a citizen of the United States, residing at Constantine, in the county of St. Joseph and State of Michigan, have invented certain new and useful Improvements in Shifting-Rails for Vehicles, of which the following is a specification, reference being had to the accompanying drawings.

10 This invention relates to improvements in shifting-rails for buggies, and is designed to produce a device, simple and efficient in operation and construction, whereby a top may be used or dispensed with at pleasure.

15 In describing the device reference is had to the annexed drawings, in which Figure 1 represents a side elevation of a buggy-body with a top attached; Fig. 2, a perspective of a seat, showing the shifting-rail applied; Fig. 3, a perspective with the same removed, and Fig. 20 4 a perspective of the shifting-rail removed from the seat.

A designates a seat with a back, B, supported on projecting strips C. A bar, D, extends around the outer edge of the seat, at a short distance from it, and rests on the projecting ends of the strips C. Each of the bars supporting the back, near its point of contact with the strips C, is recessed, said recess being undercut into the bars, forming thereby a projection, E. Under these projections or

shoulders rests the upper edge of bar D, the side pieces thereof being secured by bolts F. Strips G also project from the rear ends of the sides of the seat, and have secured to them bolts H, having one end formed into a hook, which engages over the bar or rail D. This bolt carries a projecting strip, I, which is secured to the rail D, and serves to stiffen the same, as well as secure the said bolt. The free ends of the rail are formed into spindles K, to which is pivoted the frame of the top, it being also pivoted at the rear to spindles L, which project from the said rail.

It is evident that by removing the bolts F and H the bar or rail, with the top, may be quickly removed and as quickly attached again.

What I claim is—

The combination, with a vehicle-seat having a back provided with recessed and shouldered supports, of a shifting-rail carrying the top, said rail resting in the recesses E, and removably secured by hooked bolts H, provided with stiffening-strips I, substantially as shown and described.

In testimony whereof I affix my signature in presence of two witnesses.

GEORGE STRAW.
